(57) **CLAIM**

The ornamental design for a holding tool for plastic-made caps, as shown and described.

DESCRIPTION

FIG. 1 is a front elevational view of a holding tool for plastic-made caps showing my new design;

FIG. 2 is a rear elevational view thereof;

FIG. 3 is a top plan view thereof;

FIG. 4 is a bottom plan view thereof;

FIG. 5 is a right side elevational view thereof; and

FIG. 6 is a left side elevational view thereof.

FIG. 7 is a front perspective view thereof;

FIG. 8 is a partially enlarged front elevational view thereof taken along lines 8-8 and 8'-8' shown in FIG. 1

FIG. 9 is a partially enlarged rear elevational view thereof taken along lines 9-9 and 9'-9' shown in FIG. 2;

FIG. 10 is a cross-sectional view thereof taken along line 10-10 shown in FIG. 8;

FIG. 11 is a cross-sectional view thereof taken along the line 11-11 shown in FIG. 8;

FIG. 12 is a partially enlarged front elevational view thereof taken along lines 8-8 and 8'-8' shown in FIG. 1;

FIG. 13 is a combined sectional view taken along line 13-13'-13" as shown in FIG. 12.

FIG. 14 is a partially enlarged front perspective view thereof taken along lines 8-8 and 8'-8' shown in FIG. 1 and ;

FIG. 15 is a partially enlarged rear perspective view thereof taken along lines 9-9 and 9'-9' shown in FIG. 2;

FIG. 16 is a referential cross-sectional view thereof taken along line 10-10 shown in FIG. 8, showing a state of use; and,

FIG. 17 is a referential partially enlarged front perspective view thereof taken along lines 8-8 and 8'-8' shown in FIG. 1 showing the state of use.

The broken line in the drawings is included for the purpose of illustrating environment, and forms no part of the claimed design. The alternate long and short dash line denotes the boundary between the claimed design and unclaimed parts.

1 Claim, 17 Drawing Sheets
